DESIGN FOR A HOOK ATTACHING DEVICE FOR FISHING LINES OR SIMILAR ARTICLE

Margery Baird, Woodbury, N. J.

Application May 31, 1944, Serial No. 113,820

Term of patent 14 years

(Cl. D31—1)

To all whom it may concern:

Be it known that I, Margery Baird, a citizen of the United States, residing at Woodbury, in the county of Gloucester and State of New Jersey, have invented a new, original, and ornamental Design for a Hook Attaching Device for Fishing Lines or Similar Article, of which the following is a specification, reference being had to the accompanying drawing, forming part thereof.

Figure 1 is a view in perspective of a hook attaching device for fishing lines or similar article embodying my new design.

I claim:

The ornamental design for a hook attaching device for fishing lines or similar article, substantially as shown.

MARGERY BAIRD.
